UNITED STATES PATENT OFFICE.

ERRETT LUCAS MORSE, OF LOS ANGELES, CALIFORNIA, ASSIGNOR TO PORTER INCORPORATED, OF SAN DIEGO, CALIFORNIA, A CORPORATION OF CALIFORNIA.

TIMER.

Application filed March 24, 1921. Serial No. 454,991.

To all whom it may concern:

Be it known that I, ERRETT LUCAS MORSE, a citizen of the United States, residing at Los Angeles, in the county of Los Angeles and State of California, have invented new and useful Improvements in Timers, of which the following is a specification.

It is the object of this invention to provide a timer for the ignition system of an internal combustion engine and of the type including a rotatable commutator mounted upon the cam shaft of the engine and arranged to successively engage a plurality of contact brushes carried by a casing supported against the engine frame and received over the end of the cam shaft which carries the rotating commutator.

It is the specific object of the invention to so arrange the contact brushes carried by the casing as to be readily reversible when worn at one end, and to also provide a rotating commutator which may be similarly reversed when one side has become worn.

Further objects of the invention will be readily understood from the following description of the accompanying drawings, in which—

Figure 1 is a longitudinal section through a timer constructed in accordance with the invention.

Fig. 2 is a front elevation of the same with the casing partly broken away.

Fig. 3 is a front elevation of the rotating commutator.

Fig. 4 is an elevation showing a portion of the casing and one of the contact brushes.

Figs. 5 and 6 are detail sections on the lines 5—5 and 6—6 of Fig. 4.

In the drawings, a usual engine frame is shown at 1 having the projecting cam shaft 2 adapted to carry the rotating commutator of the timer. A casing 3 is mounted over the end of the cam shaft received against the engine frame 1 so as to be rotatably adjusted through an arm 4 with relation to the cam shaft in order to advance or retard the spark in the usual manner.

The rotating commutator of the timer includes a sleeve 5 received upon the end of the cam shaft and having a flange 6 at its rear end for positioning the rotating commutator. The rotating commutator is an annular member received upon sleeve 5 and having a radial notch 7 at its axial opening

which is adapted to receive a lug 8 bent from flange 6 of the sleeve 5 in order to fix the rotating commutator with relation to sleeve 5. A sleeve 9 is received over sleeve 5 and abuts against the rotating commutator to hold the latter against axial movement, and sleeves 9 and 5 are fixed with relation to the cam shaft by means of a usual set screw 10 and a usual end nut 11.

The rotating commutator includes an annular member 12, preferably of metal and having annular members of insulating material, as shown at 13, received against the respective surfaces of annular member 12. A contact member is fixed against the respective insulator rings 13, and each of said contact members is shown as an arcuate ring 14, preferably of copper and extending around substantially the entire circumference of the rotating contact, with a contact member 15 in the circumference of ring 14 and between the ends thereof. Contact members 16 are also arranged in the circumference of ring 14 between the ends of the latter and the contact member 15, the contact members 15 and 16 being preferably also of copper and spaced circumferentially from one another and from the ends of ring 14. Ring 14 and contacts 16 are secured against insulators 13 and to the member 12 by suitable rivets 18 which are provided with insulator bushings 19 so that the ring 14 and the contacts 16 are non-electrically connected to member 12, forming a part of the circuit through the timer, by means of sleeves 9 and 5 and the cam shaft 2. The contacts 15, on the other hand, are electrically connected to member 12 as by rivet 20 securing said contacts against the respective insulators 13 and making electrical connection with member 12.

The contact brushes upon the casing of the timer are circumferentially spaced and are adapted to engage the surface of the rotating contact which is turned outwardly, so as to close circuits through the respective contact brushes as contact 15 passes over said contact brushes in the casing. It will be understood that, as ring 14 passes over the respective casing contact brushes, circuits through the same are broken, and that the provision of the non-circuit closing contacts 16 between contact 15 and ring 14 and spaced from the same, will prevent

a circuit being closed through one or more of the casing contact brushes at a time, as contact 15 successively moves into engagement with the casing contact brushes.

- 5 The casing contact brushes are preferably supported by the end wall of casing 3, and each includes a socket member 25 received against the end wall and formed of suitable electrical conducting material, with 10 a terminal bolt 26 projecting from the socket member through the end wall of the casing so as to receive a usual nut 27 upon its outer end in order to form a terminal connection. An insulator bushing 28 surrounds each of the terminal bolts 26 and sockets 25 are insulated from the end wall of casing 3 by means of an insulator ring 29 received between sockets 25 and the wall of casing 3. In order to prevent rotation 15 of socket members 25, a second insulator ring 30 is mounted upon insulator ring 29 and is provided with openings adapted to receive sockets 25. The sockets are non-circular in cross section and the openings in 20 the rings 30 receiving the same are of similar shape, so that the sockets are held against turning movement.

The contact brushes received within the sockets 25 preferably each consists of a plug 32 adapted to be reversibly received in sockets 25 so that when one end of the plug has become worn, it may be reversed in order to present the unworn end to the rotating contact. The plugs 32 are preferably of carbon in order that electrical circuits may be closed through the same and through contact 15, which is of copper, without making it necessary to oil the timer.

40 In order to prevent accumulation of oil within the timer casing, the bottom of the same may be provided with a drain opening 33. The contact brushes are yieldably urged into engagement with the rotating commutator, and for this purpose, leaf 45 springs 34 are secured at one end to sockets 25 as shown at 35, with the opposite ends of the leaf springs received in slots 36 of sockets 25 and engaging the apertures 37 extending through the contact plugs. It 50 will be understood that apertures 37 are positioned midway of the lengths of the contact plugs in order to make possible the ready reversing of the same.

55 By reference to Fig. 2, it will be seen that the ends of arcuate member 14, and the sides of contacts 16 and of contact 15, are radially disposed with relation to the timer in order to form radial insulator spaces between contact 15 and contacts 16, and between these latter contacts and the ring 14. In similar manner the sides of contact plugs 32 are radially disposed with relation to the timer, and as a consequence 60 as the commutator rotates, circuit closing

contacts are made along radial lines instead of at single points.

It will be apparent that various changes may be made in the constructions just described without departing from the spirit of the invention.

70 What is claimed is:

1. A timer comprising a contact member fixed in a rotating head but reversible therein and a casing carrying circumferentially spaced sockets adapted to receive contact 75 plugs which are fixed therein but adapted to be taken out and reversed and which are adapted to engage the adjacent surface of the rotating contact member.

2. A timer comprising a rotatable reversible contact member, an arcuate strip upon the surface thereof, a contact between the ends of said arcuate contact strip, said strip forming a non-conductor and said contact forming a conductor, and a casing carrying 85 a plurality of circumferentially spaced sockets adapted to receive reversible contacts adapted to engage the strip and contact of the rotating contact member.

3. A timer comprising a casing having 90 circumferentially spaced reversible contacts and a rotating reversible contact member adapted to successively engage said casing contacts and comprising an annular member forming an electrical conductor, insulator 95 members against the respective surfaces of said annular member, and contacts received against the respective insulator members and secured in position by a rivet forming electrical connection between said annular 100 member and said contacts.

4. A timer comprising a rotating contact member and a casing having a plurality of sockets forming terminals projecting from said casing and insulated from the latter, 105 said sockets carrying reversible contact plugs adapted to engage said rotating contact members which contact plugs are provided with recesses and resilient means 110 having portions engaging in the recesses in said plugs for yieldably urging the same into engagement with the rotating contact member.

5. A timer comprising a rotatable reversible contact maker having sides radially disposed with relation to the timer, and a casing carrying a plurality of circumferentially spaced reversible spring pressed contacts 115 adapted to be engaged by the contact maker, said contacts having sides radially disposed with relation to the timer and being provided with apertures that receive parts of the springs that press said contacts into engagement with said contact maker.

120 In testimony whereof I have signed my name to this specification.

ERRETT LUCAS MORSE.
